[57] CLAIM

[21] Appl. No.: 366,170

The ornamental design for a combined fish hook and
 line dispenser and storage container, as shown and de-
 scribed.

[22] Filed: Apr. 7, 1982

DESCRIPTION

[52] U.S. Cl. D22/99; D3/38;
 D22/13; D22/22

FIG. 1 shows a top view of a combined fish hook and
 line dispenser and storage container of my invention
 showing the fish hook and line in phantom for illustra-
 tive purposes only.

[58] Field of Search 224/920; D3/38;
 43/57.2, 57.3, 43.11, 25.2; D22/13, 22, 99

FIG. 2 illustrates an end view of the container.
